METAL CULVERT.

937,876.

Specification of Letters Patent. Patented Oct. 26, 1909.

Application filed March 26, 1909. Serial No. 485,913.

To all whom it may concern:

Be it known that we, FRANK A. SICKLESTEEL and FREDERICK C. BALLARD, citizens of the United States, residing at North Branch, in the county of Lapeer and State of Michigan, have invented certain new and useful Improvements in Metallic Culverts; and we do hereby declare the following to be a full, clear, and exact description of the invention, such as will enable others skilled in the art to which it appertains to make and use the same.

Our invention relates to metallic culverts and more particularly to that class of culverts built up of a plurality of separable sections.

One object of our invention is the provision of novel means for releasably interlocking the side sections with the bottom section against the possibility of accidental disengagement.

Another object is the provision of novel means for retaining the side sections in interlocked position relative to the bottom section.

To these ends, therefore, our invention consists in certain novel features and combinations of parts such as will be more fully described hereinafter and particularly pointed out in the claims.

In the accompanying drawings, Figure 1 is a view in side elevation of a culvert embodying our invention, Fig. 2 is a cross-sectional view and Fig. 3 is a detail view showing the locking tongue.

It is well known that in culverts of the type shown in the drawings, it is necessary to afford means for permitting expansion and contraction, due to temperature changes.

Furthermore, it frequently occurs that the earth beneath the culverts will wash out and to prevent the disengagement of the culvert sections, due to the removal of the supporting earth, we have devised a construction which, when assembled, will hold the bottom suspended, thus preserving the continuity of the culvert, in case the supporting material beneath should wash away.

Referring to the drawings, 1, 1 indicate the concavo-convex side sections, the upper edges thereof being provided with interlocking sutures 2, 2, forming a strong, yet yielding joint.

The interlocking feature of our invention is constructed as follows: The straight bottom edges of the side sections are provided

with projecting approximately T-shaped tongues 3 which are curved in substantially the same arc as are the sides. The bottom section 4 is provided along its opposite sides with downset ledges 5, whereby the shoulders 6 are formed at the juncture of the ledges and the body portion of the bottom section. Substantially T-shaped slots are formed in the bottom section, such slots lying partially in the bottom section and the narrow portions 7 of such slots extending into the ledges 5, 5. The outer walls of the narrow portions 7 of the slots are beveled as at 8, as are the abutments 9 formed at the juncture of the wider portions 10 with the narrower portions 7 of the slots.

In assembling the culvert, the side sections are inclined away from each other and at an angle to the base in order that the tongues 3 may pass over the inclined abutments 9 and be inserted in the wider portions 10 of the slots. When the tongues are inserted, the edges 11 of the sides engage the faces of the shoulders 6 which serve as fulcrums for the sides as they are swung toward each other to proper position. As the sides are moved toward each other, the tongues are swung outward and their recesses 12 caused to receive the abutments 9, thereby positively locking the base to the sides, so that even though the support beneath the base were to give way, the base would be held in place by the sides. The upper edges of the sides intermatch as shown, when the culvert is assembled, to form a strong joint.

From the foregoing it will be seen that we have devised a simple and efficient means for positively locking the base and sides together against the possibility of separation unless the culvert is disassembled by swinging the side walls away from each other. The sections are arranged to break joints, that is to say, the sides break joints with each other and with the bottom sections so that the culvert cannot separate longitudinally in case the supporting material between the ends or at either end is removed. It is evident, also, that changes might be made in the form and arrangement of the several parts described without departing from the spirit and scope of our invention.

Having thus fully disclosed our invention, what we claim as new, is:

1. A culvert comprising sides and a bottom, the bottom provided with a series of slots, which slots are narrower at their outer

- than at their inner ends, and tongues on the sides, the tongues being recessed and receivable in the slots, the walls of the narrower portions of the slots adapted to be received in the recesses in the tongues whereby to releasably and positively lock the sides and bottom together.
5. A culvert comprising sides and a bottom, recessed tongues protruding from the lower edges of the sides, fulcruming means located adjacent each longitudinal edge of the bottom, the bottom also provided with a series of slots which are narrower at one end than at the other, and sides co-acting with the fulcruming means to swing the tongues so that their recesses will receive the walls of the narrower portions of the slots.
6. A culvert comprising a bottom and sides, recessed tongues carried by the sides, a downset ledge extending along each longitudinal edge of the bottom, whereby a shoulder is formed at the juncture of the sides and bottom, the bottom having slots formed therethrough and extending into the ledges, which slots are wider at one end than at the other, to receive the tongues, the walls of the narrower portions of the slots adapted to be received in the recesses in the tongues.
7. A culvert comprising a bottom and sides, recessed tongues carried by the sides, the bottom provided with a series of slots having abutments extending thereinto to restrict the width of the slots at one end, the abutments being beveled to permit the insertion of the tongues only when they lie at an angle to the bottom, the abutments receivable in the recesses in the tongues when the sides are in assembled position.
- In testimony whereof, we affix our signatures in presence of two witnesses.
- FRANK A. SICKLESTEEL.
FREDERICK C. BALLARD.
